UNITED STATES PATENT OFFICE.

WALTER M. MATHES, OF CHESTER, PENNSYLVANIA, ASSIGNOR TO CONGOLEUM COMPANY, INC., OF NEW YORK, N. Y., A CORPORATION OF NEW YORK.

MACHINE FOR FOLDING AND ATTACHING RIBBONS TO THE EDGES OF FLOOR COVERINGS.

Application filed August 28, 1923. Serial No. 659,851.

To all whom it may concern:

Be it known that I, WALTER M. MATHES, a citizen of the United States, residing in Chester, Pennsylvania, have invented a Machine for Folding and Attaching Ribbons to the Edges of Floor Coverings, of which the following is a specification.

This invention relates to mechanism for applying to the edges of floor coverings, such as oil cloth and linoleum, a reinforcing or binding ribbon, although it will be understood that the machine may find useful application in binding the edges of strip materials other than floor coverings.

The invention resides in novel details of construction hereinafter set forth and illustrated in the attached drawings, in which:

Figure 1, is an elevation of apparatus made in accordance with my invention;

Fig. 2, is a section on the line 2—2, Fig. 1; Fig. 3, is a section on the line 3—3, Fig. 1;

Fig. 4, is a section on the line 4—4, Fig. 1;

Fig. 5, is a plan view of one side of that portion of the apparatus shown at the right in Fig. 1;

Fig. 6, is an elevation of that portion of the apparatus illustrated in Fig. 5;

Fig. 7, is a view in perspective of that end of the guide frame illustrated in Figs. 5 and 6;

Fig. 8, is a view in perspective of one of the guide and ribbon folding units which are mounted upon the ends of the frames illustrated in Fig. 3;

Fig. 9, is a fragmentary plan view of that end of the apparatus shown at the left in Fig. 1;

Fig. 10, is a side elevation of that portion of the apparatus shown in Fig. 9;

Fig. 11, is a view in perspective of that end of the guide frame illustrated in Figs. 8 and 9;

Fig. 12, is a view in perspective of the frame supporting and guide head at that end of the apparatus shown at the left in Fig. 1, and

Fig. 13, is a view in perspective of one of the ribbon guide elements.

With reference to the drawings, the apparatus comprises at one end a suitable pedestal or support 1 upon which is supported a cross beam 2, said cross beam constituting a support for one end of a bed plate 3 which at the other end is supported upon blocks

4, 4, carried by tables 5, 5, at the top of pedestals 6, 6.

Attached to the cross piece 2, one at each side is a flat topped member 7 constituting each a support for one end of a pair of guide frames 8, 8, the opposite ends of which are supported on the tables 5, 5. That end of each of the frames 8 which rests upon the supports 7 is illustrated in Figs. 5, 6 and 7, and as shown, this end of the frame carries a sub-frame 9, as shown in Fig. 8, provided with a roller 11 whose axis occupies a position longitudinally of the frame and rests upon the support 7, this roller providing for lateral movement of that end of the frame on the said support. The opposite ends of the said frames 8, 8, as illustrated in Fig. 11, are each provided with a pair of rollers 12, 12, whose axes also are longitudinal of the frame, said rollers riding upon suitable tracks 13 on the tables 5 and providing for lateral movement of these ends of the said frames 8, 8. Longitudinal movement of the frames is prevented by means of pins 10, Fig. 5, projecting upward from the supports 7 into lateral slots 10^a in sub-frames 9.

The opposite ends of the frames 8, 8, are bound together by means of resilient elements such as the springs 14 and 15, said springs tending to hold the said frames together while permitting separation laterally under pressure. As illustrated in Fig. 8, each of the sub-frames 9, 9, is provided with a grooved roller 16 vertically journaled in suitable brackets 17, and a plain vertical roller 18, the function of which will be described hereinafter. That end of each of the frames 8, 8, illustrated in Fig. 11 is provided with a sub-frame 19, in which is journaled on a vertical axis a grooved roller 21 and on horizontal axes two sets of plain faced rollers 22, 22, and 23, 23, the rollers of the respective sets being adjustable by means of set screws 24, 24, to and from their companion rollers. The bracket boxes 19 also each carries a guide arm 25, the function of which will be described hereinafter. As clearly shown in Figs. 7 and 11, the outer edge of each of the frames 8, 8, is turned up and back.

In operation, a strip of the floor covering or other material whose edges are to be bound, which strip is indicated in the draw-

ings by the reference numeral 26, is fed by suitable feeding mechanism between the frames 8, 8, said strip resting upon the base plate 3, as illustrated in Fig. 4, and having 5 its side edges disposed in the grooves of the rollers 16 and 21 of the respective side plates. The springs 14 and 15 exert a pressure upon the side frames 8, 8, tending to pull them together and so hold them firmly against 10 the side edges of the strip, any variations in the width of the strip being accommodated by expansion of the structure and separation of the side frames 8, 8, permitted by the springs 14 and 15. It will also be noted 15 that the edges of the said strip pass between the turned over outer edges of the said side frames 8, 8, as clearly illustrated in Fig. 3. Also as best illustrated in Fig. 4, the edges of the said strip pass between the respective 20 sets of rollers 22, 22, and 23, 23, which by means of the set screws 24, 24, are adjusted to bear with the required amount of force on the opposite side of the strip.

Extending one at each side of the frame 25 from the supports 27 is a spindle arm 28 adapted to support a spool 29 of the binding ribbon α , said ribbon passing from the spindle around the roller 18 and rearwardly and between the compression rollers 22, 22, 30 and 23, 23, which as previously described pass one on either side of the said strip. In passing from the roller 18 to the pressure rollers 22 and 23, the ribbons pass along the turned over edge of the side frames 8 and 35 in back of a suitable guide 31 shown in Fig. 13 and secured as illustrated in Figs. 9 and 10 to the said side frames 8. In passing between the pressure rollers 22, 22, and 23, 23, the ribbon is folded over the edge of the 40 strip, the flanged edges of the side frames and the guide element 31 insuring the proper folding of the ribbon over the edge. The arms 25, 25, on the box brackets 19 constitute a guide for steadyng the strip of fabric 45 as it passes between the rollers 22 and 23, and further insure the proper positioning of the reinforcing ribbon on the edges. The action of the moving strip and of the pressure rollers 22, 22, and 23, 23, constitute the 50 actuating means for drawing the ribbon from the spool and passing it through the apparatus.

A pair of trimming rollers 32, 32, which trim the strip of flooring or other material 55 and insure a strip of uniform width may be mounted at each side upon the pedestals 1. These trimming rollers, however, are not essential to the operation of the apparatus aforescribed.

As the strip leaves the rollers 22—23, an operator may be so positioned at each side to apply lables or other securing elements to secure the said ribbon to the strip, or an adhesive may be applied to the ribbon prior to its being folded over the strip. In some

instances, it may be found unnecessary or undesirable to secure the ribbon to the strip by any securing means other than the natural tendency of the ribbon to remain over the edges of the strip when the latter is rolled up.

I claim:

1. The combination with strip feeding mechanism, of a laterally expansible structure having guides for the side edges of a strip actuated by said feeding mechanism, and mechanism mounted on and movable with said structure for applying a reinforcing ribbon to the edge of said strip.

2. The combination with strip feeding mechanism, of a laterally expansible structure having guides for the side edges of a strip actuated by said feeding mechanism, a spool for a reinforcing ribbon, and mechanism carried by said structure for folding ribbon from said spool over the edge of and applying said ribbon to said strip.

3. The combination with strip feeding mechanism, of a laterally expansible structure comprising two relatively movable side members each having guides for the side edges of a strip actuated by said feeding mechanism, a spool for a reinforcing ribbon, and mechanism for withdrawing ribbon from said spool and for holding it longitudinally over and applying it to the edge of said strip. 90

4. The combination with strip feeding mechanism, of a laterally expansible structure comprising two relatively movable side members each having guides for the side edges of a strip actuated by said feeding mechanism, and mechanism carried by said members and including a pair of rollers adapted to bear against opposite sides of the strip at the edge for applying a reinforcing ribbon to the strip at said edge. 100

5. The combination with strip feeding mechanism, of a laterally expansible structure comprising two relatively movable side members each having guides for the side edges of a strip actuated by said feeding mechanism, a spool for a reinforcing ribbon, a pair of rollers on opposite sides of the strip carried by the respective side members adapted to fold ribbon from said spool over the edge of the strip, and strip guiding means also carried by the side members intermediate the spool and said rollers. 110

6. The combination with strip feeding mechanism, of a pair of side frames laterally movable with respect to each other and having guides for the side edges of a strip actuated by said feeding mechanism, resilient means tending to retain the said frames firmly against the edges of said strip, and mechanism mounted on said frames for applying a reinforcing ribbon to the edge of said strip. 120

7. The combination with strip feeding

- mechanism, of a pair of side frames laterally movable with respect to each other and having guides for the side edges of a strip actuated by said feeding mechanism, resilient means tending to retain the said frames firmly against the edges of said strip, means for preventing movement of the frames longitudinally of the strip, and mechanism mounted on said frames for applying a reinforcing ribbon to the edge of said strip.
8. The combination with strip feeding mechanism, of a supporting structure having rollers, members mounted on said rollers and engaging the opposite sides of said strip, resilient means for holding said members against the strip, and means mounted on each of said members for applying a reinforcing ribbon to the edge of said strip. 16

WALTER M. MATHEIS.
